UNITED STATES PATENT OFFICE.

EDWARD A. JONES, OF SCRANTON, AND JOHN E. JONES, OF THROOP, PENNSYLVANIA.

GRAPHITE LUBRICATOR.

1,145,314.

Specification of Letters Patent.

Patented July 6, 1915.

Application filed September 23, 1913. Serial No. 791,406.

To all whom it may concern:

Be it known that we, EDWARD A. JONES and JOHN E. JONES, citizens of the United States, residing at Scranton and Throop, respectively, in the county of Lackawanna and State of Pennsylvania, have invented certain new and useful Improvements in Graphite Lubricators, of which the following as a specification.

10 Our invention relates to new and useful improvements in automatic lubricators, the object of our invention being to provide a lubricator for feeding graphite or any lubricants manufactured in solid form to the 15 valves of steam engines, the pistons of engines or any other moving parts for which such lubricant may be intended.

20 A further object of our invention is to construct a lubricator by means of which 25 stick graphite may be ground and fed to the parts to be lubricated together with lubricating oil, the graphite being ground and the oil supplied thereto after it is ground and before it passes to the parts being lubricated.

25 A still further object of our invention is to provide a steam jet adapted to work in conjunction with the grinding mechanism, so arranged that the steam supply passes 30 with the graphite and oil to the engine.

35 A still further object of our invention is to provide means whereby any moving part of the engine being lubricated may be employed to actuate the grinding mechanism 40 of the lubricator. And, a still further object of our invention is to provide means whereby the quantity of graphite ground and fed to the machinery may be varied at will.

45 With these and other objects in view, our invention will be more fully described, illustrated in the accompanying drawings and then specifically pointed out in the claims which are attached to and form a part of this application.

50 For a full understanding of the invention reference is to be had to the following description and accompanying drawing, in which:—

55 Figure 1 is a sectional view of a conventional form of steam engine, showing the manner of employing our lubricator to supply graphite and oil to the slide valve controlling the admission of steam to the cylinder. Fig. 2 is a vertical sectional view of our lubricator proper taken upon the line 2—2 of Fig. 3. Fig. 3 is a transverse sec-

tional view on the line 3—3 of Fig. 2, showing certain details of the grinding mechanism.

60

Corresponding and like parts are referred to in the following description and indicated in all the views of the accompanying drawings by the same reference characters.

Referring more specifically to Figs. 2 and 3 of the drawings it will be seen that our improved lubricator includes a body proper formed in two principal parts 10 and 11. The body portion 10 is tubular in shape throughout the greater portion of its length, 70 being externally threaded at one end, as shown at 12 for threaded engagement in the wall of the steam chest or other similar structure and being provided intermediate its length with a laterally directed, externally threaded nipple 13 to receive an oil cup shown conventionally in Fig. 1, at 14. The upper end of the lower body member 10 is enlarged to provide a circular housing 15, eccentrically located with respect to the tubular portion and having an upstanding circumferential flange 16 provided with external threads. The upper portion 11 of the body of the lubricator includes a tubular part 17 adapted to extend in a line with the tubular portion 10 and an exteriorly formed extension 18 providing a cap for the housing 15 and coacting therewith to provide a chamber 19. The circumferential edge of this extension, in connection with a portion 90 of the edge of the tubular part 17 provides a flange which is interiorly threaded for threaded engagement about the flange 16 of the housing 15, and both the tubular part 17 and extension 18 are provided with an 95 inwardly directed flange 20 which seats upon the upper edge of the flange 16 when the parts are assembled. The tubular part 17 at its lower end is provided with an inwardly directed circumferential flange 21, 100 the purpose of which will be hereinafter explained.

Both the above described parts are preferably cast or otherwise formed of brass or other suitable material and cast integrally 105 with the extension 18 is a diagonally disposed jet nozzle 22 which extends through the wall 18 and has its outer end externally threaded as at 23 to receive a steam supply pipe. The inner end of this nozzle is directed toward the lower end of the tubular part 17 of the upper body member 11. The upper body member 11 is provided adjacent its upper end with an encircling

110

shoulder 24 and is threaded externally beyond the shoulder to receive a cap 25, the edge of which engages against the shoulder 24 when the cap is in place, this cap preferably extending a considerable distance above the upper end of the body member and being provided interiorly with a socket forming a continuation of the bore of the body member.

10 The housing 15 is provided centrally with a packing box 27 having the usual packing gland 28 and packing nut 29. A shaft 30 extends through this packing box into the lower portion of the chamber 19 and secured in any suitable manner upon this shaft and against rotation independently thereof is a grinding disk 31. This grinding disk is preferably rough cast and fits loosely in the housing 15, extending by one peripheral edge across the lower portion of the tubular part 17 of the upper body member 11. The disk is provided with a plurality of perforations 32, by means of which the grinding is accomplished, as will be later explained, and is formed upon its lower face with a boss 33 which seats upon the inner face of the housing 15 to support the disk in slightly spaced relation thereto. A collar 34 surrounds the shaft above the disk 31 and is held against displacement by a cotter pin 35, this pin and collar holding the disk against longitudinal movement upon the shaft.

35 The graphite employed in this lubricator is supplied in stick form and the stick is placed in the upper bore of the upper body portion 11 of the lubricator, supported by its lower end upon the upper face of the grinding disk 31 and properly centralized in the bore of the body member by the flange 21 at its lower end, and at its upper end by the downwardly directed circumferential flange 36 of a follower 37. This follower is provided centrally with an upwardly directed pin 38 forming a handle by means of which it may be raised from the body of the lubricator and also a support for radially slotted weights 39 by means of which pressure upon the stick of graphite 40 may be regulated, but one of these weights being shown. The pin 38 preferably terminates at its free end in an eye 40 in order that it may be raised by a hook or other suitable instrument after the graphite stick 45 has been entirely used.

60 The free end of the shaft 30 extends considerably below the packing box 27 and a lever-arm 41 is secured to the free end of this shaft by a set-screw 42 in such a manner that any swinging of the lever-arm in a horizontal plane will cause an oscillatory movement of the grinding disk 31. This lever-arm is provided adjacent its free end with a plurality of spaced apart bores 43 for adjustable connection to a link or any

suitable operating mechanism for transmitting power from some part of the machine being lubricated to the lubricator.

For the sake of a clear understanding of the operation of our improved lubricator 70 we have illustrated the same in Fig. 1 in connection with a conventional form of steam engine, indicated as a whole by the numeral 44 and including a steam chest 45 having a cap-plate 46 through which the 75 threaded end of the lower body member 10 is passed, a binding nut 47 threaded upon said end being turned against the cap-plate when the lubricator is in place. When so mounted a pipe 48 leading from any source 80 of steam supply is connected to the jet nozzle 22 in order to supply the requisite steam to the lubricator.

85 The lever-arm 41 may be swung by means of any suitable mechanism forming some part of the engine such as the valve-stem 49. In the present instance, this connection includes a bracket 50 clamped by one end about the valve-stem and by its other end to a link 51. This link extends in a 90 horizontal plane and its opposite end is bifurcated to provide spaced ears 52 extending one above and one below the lever-arm 41. A bolt 53 passes through perforations formed in these ears and one of these perforations 43 of the lever-arm pivotally connects the link to the lever-arm. It will be clear that the reciprocation of the valve-stem 41 will cause reciprocation of the link 51 and that this movement of the link will 100 be transmitted by the lever-arm 41 to oscillate the grinding disk 31.

105 In operation a stick of graphite is positioned in the bore of the upper body member, as shown at 54 and the steam is supplied through the pipe 48. Inasmuch as the graphite is held, by the follower and its weight or weights against the upper face of the disk 31 which is constantly oscillated, as previously described, it will be clear that the disk will constantly grind away graphite from the lower end of the stick. The steam passing through the steam jet 22 strikes against the upper face of the grinding disk and also against the lower portion of the 110 tubular part 17 and serves the double function of forcing the ground graphite through the perforations of the disk into the lower body member and of somewhat heating the disk and tubular part 17 of the body member, to thus facilitate the grinding action. The ground graphite falling through the lower body member 10 is met by oil from the oil cup 14 and the mixed graphite, steam and oil pass into the steam-chest 45. Means 115 is provided for regulating the proportion of steam supplied to the quantity of graphite ground, which latter, may be controlled by means of the weights 39. The oil cup 14 should be of such a type that the quantity of 120

oil flowing therefrom may be readily adjusted. It will therefore be clear that the exact proportions as well as the amount of steam, graphite and oil supplied to the moving parts of the engine may be accurately regulated.

Although we have illustrated the lubricator as employed for lubricating a slide-valve of a steam engine, it will also be apparent that it may be employed for lubricating any other types of engines and moving parts of machinery. It will further be clear that the construction admits of many minor changes, and for this reason we do not wish to limit ourselves in any way to the specific details of construction described in the drawings, as any desired changes, within the scope of the appended claims, may be made, without in the slightest degree departing from the scope of our invention.

What we claim is:—

1. A lubricator including a tubular body member forming a duct for the passage for the lubricant, a housing formed in the upper end of the body member, a grinding member having lubricant passages mounted in the housing, means for actuating said grinding member, and means for holding a stick of graphite in engagement with the grinding member.

2. A lubricator including a tubular body member forming a duct for the lubricant, a housing formed at the upper end of the body member, a grinding disk having unobstructed perforations mounted for rotation in said housing, means for holding a stick of graphite against the upper face of the grinding disk and in alinement with the tubular body member, and means for oscillating the disk.

3. A lubricator including a tubular body member terminating at its upper end in an eccentrically formed cylindrical housing, a disk mounted for rotation in said housing and provided with a plurality of openings, means for holding a stick of graphite against said disk, and means for directing a steam jet against the disk adjacent the stick of graphite.

4. A lubricator including a tubular body member terminating at its upper end in an eccentrically formed circular housing, a shaft extending through the lower wall of the housing, a disk secured against rotation upon said shaft and provided with a plurality of perforations, a second tubular body member adapted to extend in alinement with the first and provided at its lower end with an extension forming a cap for the housing, said second tubular body member being adapted to receive a stick of graphite and hold the same in engagement with the disk, and a jet-nozzle formed in the cap with its

inner end directed toward the base of the second tubular body-member.

5. A lubricator including a holder, for stick graphite, means for grinding graphite from the stick, means for supplying steam to the grinding means, and means for supplying the ground graphite and steam to movable parts to be lubricated.

6. A lubricator including a holder for stick graphite, means for grinding graphite from the stick, means for supplying steam to the grinding means, means for supplying the ground graphite and steam to movable parts to be lubricated and means for supplying oil to the mixture of graphite and steam before it reaches said movable parts.

7. A lubricator including a body member providing a chamber and a duct leading from the chamber, means for supplying a jet of steam to the chamber, a grinding disk located in the chamber, means for holding a stick of graphite against the grinding disk, and means for supplying oil to the duct.

8. A lubricator including a graphite stick holder, and a grinding member mounted for movement in position to engage a stick of graphite in the holder, said grinding member being provided with a plurality of lubricant passages.

9. A lubricator including a graphite stick holder, and a grinding member mounted for movement in position to engage a stick of graphite in the holder, said grinding member being provided with a plurality of lubricant passages and with a plane surfaced abrasive face against which the graphite is held.

10. A lubricator including a grinding member, means for holding a stick of graphite against the grinding member, and means for directing a steam jet against the grinding member.

11. A lubricator including a grinding member, means for holding a stick of graphite against the grinding member, and means for directing a steam jet against the grinding member, the graphite holding means protecting the graphite from exposure to the steam.

12. A lubricator including a holder for stick graphite, means for grinding graphite from the stick, means for supplying oil to the ground graphite, and means for supplying the ground graphite and oil with steam to movable parts to be lubricated.

In testimony whereof we affix our signatures in presence of two witnesses.
